[57] CLAIM

The ornamental design for a combined water treatment and storage unit, as shown and described.

DESCRIPTION

FIG. 1 is a top plan view of a combined water treatment and storage unit showing our new design;

FIG. 2 is front elevational view thereof, the rear being plain and unornamented;

FIG. 3 is a right side elevational view thereof;

FIG. 4 is a bottom plan view thereof;

FIG. 5 is a perspective view taken from the top, front and left side thereof; and

FIG. 6 is a left side elevational view thereof.

FIG-1

FIG-2

FIG-3

FIG-4

FIG-5

FIG-6
